UNITED STATES PATENT OFFICE.

EDWARD HAMMANN, OF BROOKLYN, ASSIGNOR TO THE J. L. MOTT IRON WORKS, OF NEW YORK, N. Y.

DESIGN FOR A URINAL.

SPECIFICATION forming part of Design No. 21,957, dated November 1, 1892.

Application filed October 7, 1892. Serial No. 448,150. Term of patent 7 years.

To all whom it may concern:

Be it known that I, EDWARD HAMMANN, a citizen of the United States, residing at Brooklyn, in the county of Kings and State of New York, have invented a new Design for Urinals, of which the following is a specification.

Urinals having a back and a projecting bowl have heretofore usually been elliptical in configuration both at the back and the bowl portions.

The leading feature of my design relates to the quadrangular shape and configuration with rounding corners.

In the drawings, Figure 1 is an elevation, 15 and Fig. 2 a plan view, of the urinal.

The general configuration of the back of the urinal is quadrangular, with vertical edges *a a*, horizontal edges *b b*, and rounding corners *c c*. The bowl has a nearly-straight front *d*, with compound curved sides extending to the back. 20

I claim—

The design for a urinal, substantially as described and shown.

Signed by me this 30th day of September, 25 1892.

EDWARD HAMMANN.
